UNITED STATES PATENT OFFICE.

SUSAN CARVER, OF SHARON, PENNSYLVANIA.

DESIGN FOR A BUTTON-PLATE.

SPECIFICATION forming part of Design No. 29,328, dated September 13, 1898.

Application filed August 3, 1898. Serial No. 687,645. Term of patent 7 years.

To all whom it may concern:

Be it known that I, SUSAN CARVER, a citizen of the United States, residing at Sharon, Pennsylvania, have invented and produced a 5 new and original Design for Button-Plates, of which the following is a specification.

In the drawings, Figure 1 is a face view of my design, and Fig. 2 is an edge view.

The leading feature of the design is in the 10 outline of the plate. This consists of a plate A, having continuous straight parallel edges and a rounded end, and at its opposite end the plate is provided with a V-shaped notch.

The ends of the plate on each side of the notch are straight and are at right angles to the parallel sides. One edge of the plate is provided with graduations.

What I claim is—

The design for a button-plate as herein shown and described.

In testimony whereof I affix my signature in presence of two witnesses.

SUSAN CARVER.
